DESIGN FOR A VENDING MACHINE

Edgar H. Sargent and Anastasius G. Alex, Evanston, Ill.

Application July 15, 1940, Serial No. 93,658

Term of patent 14 years

To all whom it may concern:

Be it known that we, Edgar H. Sargent and Anastasius G. Alex, citizens of the United States, residing at Evanston, in the county of Cook and State of Illinois, have invented a new, original, and ornamental Design for a Vending Machine, of which the following is a specification, reference being had to the accompanying drawing, forming a part thereof.

In the drawing the figure is a front perspective view of a vending machine showing our new design.

We claim:

The ornamental design for a vending machine, substantially as shown.
